UNITED STATES PATENT OFFICE.

JOHN A. FLEMINGS, OF SHARON, MASSACHUSETTS, ASSIGNOR TO B. F. STURTEVANT COMPANY, OF HYDE PARK, MASSACHUSETTS, A CORPORATION OF MASSACHUSETTS.

UNDERFEED STOKER.

Application filed May 22, 1920. Serial No. 383,446.

To all whom it may concern:

Be it known that I, JOHN A. FLEMINGS, a citizen of the United States, residing at Sharon, in the county of Norfolk and State of Massachusetts, have invented certain new and useful Improvements in Underfeed Stokers; and I do hereby declare the following to be a full, clear, and exact description of the invention, such as will enable others skilled in the art to which it appertains to make and use the same.

The invention relates to underfeed stokers.

The object of the invention is to provide a stoker of this character, the parts of which are simple and rugged in construction and may be economically manufactured and conveniently assembled or replaced and which, when assembled, are accurately maintained in correct relation to each other during the continued use of the stoker.

An important feature of the invention relates to the grate structure which consists of a number of unitary grate sections each comprising a series of overlapping grate blocks arranged one above the other in step formation upon a grate bar to which they are attached by interlocking projections on the blocks and bars arranged to hold the blocks against outward or upward movement with relation to the bar, each block also being provided with a stop arranged to prevent inward movement of the underlying block and the top block being held against inward movement with relation to the bar by a coupling such, for instance, as a pin which connects this block to the bar and thus finally locks the series of blocks against displacement with relation to each other and to the bar. The parts of this structure may be cheaply manufactured, are readily assembled and when assembled are effectively locked against relative displacement without the use of numerous securing bolts and the attendant danger of working loose or becoming displaced during continued use of the stoker.

Other features of the invention relate to the construction and arrangement of the tuyère blocks with relation to the grate sections; to the means for operating the movable grate sections which enables them to be readily and accurately assembled in proper relation to each other, and to their operating means; to the mechanism through which the operating means for the movable grate

sections is driven; to the construction of the ash plates which enables them to be cheaply and conveniently manufactured and assembled or replaced; and to various other constructions and combinations of parts which contribute to economy in the manufacture and to the durability of the stoker and to the efficiency of its operation.

A single retort underfeed stoker embodying the invention in its preferred form is shown in the accompanying drawings in which Fig. 1 is a vertical cross sectional view showing a movable grate section at the left and a stationary grate section at the right of the retort, Fig. 2 is an enlarged detail of one of the stationary grate sections and overlying tuyère block, Fig. 3 is a plan view of a portion of the fuel supporting structure at the right of the retort in Fig. 1, certain parts being omitted to better show the construction beneath, Fig. 4 is a plan view partly in section showing the mechanism for operating the feed plunger and also the mechanism for operating the movable grate sections, Fig. 5 is a side elevation of the parts shown in Fig. 4, and Fig. 6 is a perspective view of a grate bar.

The underfeed stoker shown in the drawings comprises in general a retort 10, grates 12 sloping away from opposite sides of the retort and ash plates 14, these parts being supported upon vertical supporting members 16 as shown in Fig. 1. The grates 12 comprise a plurality of grate sections, each consisting of a grate bar 19 carrying a series of grate blocks 23. Tuyère blocks 25 are arranged along the sides of the retort and are supported upon the sides of the retort and upon the tops of the upper grate blocks. The space beneath the retort, grates and ash plates is divided by the supports 16 into a central air chamber 27 from which compressed air is supplied to the tuyère blocks, air chambers 28 below the grates to which air may be supplied from the chamber 27 through regulating dampers 29 and from which air is supplied to the grates, and ash pits under the ash plates to which air may be supplied from the chambers 28 through regulating dampers 31.

The upper ends of the grate bars are provided with heads 37 which rest side by side upon the top of one of the inner supports 16 and maintain the upper ends of the bars in proper spaced relation. The inner ends

of the heads are closed and in connection with the closed inner ends of the upper grate blocks completely fill the space between the upper end of the support and the bottoms 5 of the tuyère blocks and form a part of the dividing wall which separates the air supply chambers 27 and 28 for the tuyère blocks and grates respectively. The lower ends of the bars are provided with feet 38 which are 10 the same in width as the head 37 and rest side by side upon the top of an outer support 16 and maintain the lower ends of the bars in proper spaced relation. The feet of the stationary grate bars are provided with 15 depending flanges 40, 40' embracing the vertical support 16 to prevent movement of the lower ends of these grate bars with relation to the support. The feet of the movable grate bars have no flanges and are free to 20 slide forward and back over the upper surface of the support 16.

Each grate section is a unitary structure 25 consisting of the grate bar 19 and the series of overlapping grate blocks 23 arranged one above the other in step formation and interlocked with the bar and with each other. Each grate block consists of a top plate provided with a depending flange which extends along the side edges and around the curved 30 front end of the plate and forms a wall, the lower edge of which is adapted to rest upon the top plate of the underlying block. An enclosed passage is thus formed between the top plates leading to the air ports at the 35 front ends of the blocks. The top plate of each grate block, except the top block, is provided with a central slot extending forward from its inner end so that the block may straddle the grate bar and be supported centrally thereon. These slots are covered 40 by the unslotted forward parts of the overlying blocks. Each block is also provided with one or more depending hooks 30 which face outward and are arranged to engage 45 lugs 32 projecting from opposite sides of the bar 19 and thus lock the block against upward and outward movement with relation to the bar. Each block is also provided with a stop for engaging the inner end of 50 the underlying block and locking it against inward movement so that the interlocking hooks and lugs are held against disengagement. On all of the blocks except the top block the stops are formed by projections 34 55 on the hooks 30. On the top block the stops are formed by lugs 41 on the side walls of the block arranged to lie back of the inner ends of the side walls of the underlying block. Each upper grate block is provided 60 with a wall closing its inner end which rests upon the head 37 of the grate bar and forms a continuation of the closed inner end of the head. A coupling in the form of a pin 43 connects the upper block to the grate bar 65 and finally locks all of the grate blocks in

interlocking relation to the bar. The lower grate block rests upon a flat plate 36 which overlies the foot 38 of the bar and serves to close the open bottom of the lower grate block and also to close the space between the outer end of this grate block and the top of the ash plate 14.

The tuyère blocks 25 rest upon the upper surfaces of the upper grate blocks of both the stationary and movable grates and also 75 upon the sides of the retort 10. Each tuyère block is provided with a depending hook 42 adapted to hook under a flange 44 projecting from the top of the side of the retort to thereby hold the tuyère block at its inner side from upward movement. Provision is made for locking the tuyère blocks to the grate bars and for this purpose the grate bar of each stationary grate is provided with a hook 48 extended upwardly therefrom 80 through slots 49, 51 in the top of the upper grate block and bottom of the tuyère block, respectively. The hook 48 is adapted to hook over a cross bar 46 of the tuyère block. Each tuyère block is of sufficient length to 85 extend partially across the movable grates on each side of the stationary grate so that the joints between the adjacent tuyère blocks are located over the midportions of the upper grate blocks of the movable grates. The 90 tuyère blocks in this manner operate to prevent upward movement of the inner ends of the movable grates and at the same time permit reciprocation of the movable grates.

In assembling the grate sections the lower 100 grate block of each is placed upon the plate 36 supported on the feet 38 with the hooks 30 hooked under the lugs 32. Each succeeding grate block is then placed in position 105 with the hooks 30 hooked under the lugs 32 and with the inner end of the top of each grate block supported on the lugs 24. As each succeeding grate block is placed in position the stop lugs 34 depending therefrom 110 lock the underlying grate block in place, and prevent inward movement thereof.

In this manner all of the intermediate 115 grate blocks are secured upon the grate bars. After the top grate blocks have been placed in position upon the grate bars with the hook 48 of each stationary grate section extending up through a slot 49 in the top of the corresponding top grate block the lower end of each stationary grate section is lifted and moved outwardly until the hook 48 120 is brought into a position to pass up through the slot 51 in the bottom of the tuyère block. The tuyère block is then hooked under the flange 44 and lowered onto the upper grate block, the hook 48 passing up through the 125 slot 51. The grate section is then moved inwardly thereby hooking the hook 48 over the cross bar 46 and the flanged end upon the foot of the grate bar is dropped in place over the sides of the vertical support 16. 130

thereby locking the grate section and tuyère blocks from all movement except a swinging movement upwardly about the inner edge of the tuyère block as a fulcrum.

5 With this construction the grate structure including the grate bar, grate blocks and tuyère block is bound together and positively held against displacement except in an upward direction, while an upward movement 10 of any of the grate sections involves swinging the grate structure up about the inner edge of the tuyère block as a fulcrum and consequently lifting of the grate structure and the charge of the fuel thereon. There 15 is no danger, therefore, that the devices which engage and reciprocate the movable grate sections will lift and displace the grate or grate sections in case of unusual resistance to the movement of the grate sections 20 due to the sticking of the grates or other causes. Neither is there any danger that any part of the grate will be displaced by the use of a bar to break up any clinkers which may form.

25 In the operation of the stoker, the coal is fed by mechanical or other means into a hopper 50 which communicates with the forward end of the retort 10. A power driven plunger 52 feeds the coal lengthwise of the retort from which it is gradually moved laterally over the grates to the ash plates. The plunger 52 is actuated from a driven shaft 54 through a crank 56 and connecting rod 58. The connecting 30 rod may be provided with a safety device indicated at 59 constructed to give way should the forward movement of the plunger be unduly resisted and thereby avoid injury to the plunger or its operating 35 mechanism.

40 Provision is made for reciprocating alternate grate bars in order to assist in the movement of the coal from the retort to the ash plates, and for this purpose each grate bar 19 of the movable grates is provided with a depending rack 76 arranged to mesh with an operating segment 78 mounted upon a rock shaft 80 extended lengthwise of the stoker upon each side of the retort 45 10. The segment and rack 76, 78 are provided with an enlarged locating tooth 77 and tooth space 79 respectively which enable them to be properly positioned with relation to one another. Each operating 50 segment 78 is mounted upon and removably secured to the rock shaft 80 in such manner that any particular segment may be removed without the removal of the remaining segments. To this end, each segment 55 78 is provided with a yoke 94 adapted to be slipped directly over the rock shaft 80. The segment 78 is secured upon the bar rock shaft by a locking block 96 which is received within the yoke and held in 60 place by the flanged ends 98 of the yoke

and by the pin 100. Both the yoke and locking block are provided with flat surfaces which engage corresponding surfaces upon the rock shaft 80. The segments may be held in place lengthwise of the shaft by 70 any suitable means. The rock shaft 80 is preferably of hexagonal shape, as shown in Fig. 1. Each rock shaft 80 is actuated from the power driven plunger operating mechanism through a rocker shaft 82 connected therewith through bevelled gears 84 (see Fig. 4) and through an arm 86, link 88, and crank disk 90 upon the end of the plunger operating crank shaft 54. The crank disk 90 is adjustably secured by bolts 92 to the flanged end of a hub 93 secured upon the end of the crank shaft 54. The heads of the bolts 92 are received in recesses in the crank disk, as shown in Fig. 5. The movements of the crank disk 90 are 85 transmitted to the link 88 through a crank pin 102 slidably received in a slot 104 in the link. A nut 106 and washer 108 hold the link in place and a block 110 affords adjustment of the amount of lost motion between 90 the crank disk and link.

95 As previously described, the rack an segment 76, 78 are provided with an enlarged tooth 77 and tooth space 79, to enable their position with relation to one another to be definitely established and maintained. The bevel gears 84 upon the rock shafts 80 and the rocker shaft 82 respectively, are each provided with an enlarged tooth and tooth space 81, 83 so that a 100 definite relation may be established between the entire bar operating train. As only a few teeth in the bevel gears 84 are necessary to give the required motion to the grates, the gears are divided into four sections, any of which may be utilized by shifting the gears on the shafts 80 and 82, as shown in Fig. 5. The ends of both the rocker shaft 82 and rock shafts 80 are 105 squared to receive and correctly position the 110 gears 84.

115 Provision is made for reciprocating a pusher rod 112 which extends through the retort. The end of the pusher rod 112 is extended through a hole in the end of the plunger 52, and two pins 114 driven in two of a plurality of holes 116 in the rod 112 provide for lost motion between the plunger and rod.

120 In the operation of the stoker, the coal is burned in the retort 10 and upon the grates 12. The ashes are received upon ash plates 14 provided with chisel-shaped outer edges which operate to cut the clinker when the plates are rocked. Each ash plate 125 14 is supported upon and secured to a supporting plate 120. The inner end of each ash plate has two lugs 122 adapted to project under the top of a curved flange 123 on the inner end of the supporting plate. 130

The outer end of each ash plate is secured by two bolts 124 to the supporting plate. The ash plates and supporting plates are mounted upon square shafts 126. For this purpose each supporting plate 120 is provided with a square open bearing adapted to enable the supporting plate to be slipped directly over the square shaft 126. A bottom plate 132 closes the open bearing and holds the supporting plate fast upon the shaft 126, being secured to the supporting plate by bolts 134. The square shafts 126 are supported at their ends by sleeves 136 having square openings adapted to enable the sleeves to be slipped over the ends of the square shafts. The square shafts 126 are supported at points intermediate their ends by open collars 144 adapted to be slipped laterally onto the shafts and to be thereafter positioned lengthwise thereof. The collars 144 are supported in open bearings 148 in brackets 150 bolted to the vertical support 16, as shown in Fig. 1. The square shafts 126 are adapted to be turned to dump the ash plates by the manual rocking of counter-shafts 138 geared to the square shafts by bevelled gears 139. Short socket arms 140, adapted to receive a bar or other tool, are mounted upon the counter-shafts 138 and afford convenient means for dumping the ash plates. Provision is made for holding the ash plates in any desired angular position, and for this purpose a pawl 142 is provided which engages a ratchet 143 upon each counter-shaft 138, as shown in Fig. 4.

While the preferred embodiment of the invention has been illustrated and described, it will be understood that the invention may be embodied in other forms within the scope of the following claims:

1. A grate section comprising a grate bar, a plurality of overlapping grate blocks mounted thereon, one end of each block being supported on the upper surface of the underlying block, lugs on the bar for supporting the other ends of the blocks, depending hooks on the blocks, lugs on the bar with which the hooks engage to hold the blocks from movement away from the bar, and a stop on each block for holding the hook and cooperating lug of the underlying block in engagement.

2. A grate section comprising an inclined grate bar, a series of horizontal overlapping grate blocks slotted to straddle the bar, interlocking members on the blocks and bar for locking the blocks to the bar, and a stop on each block for holding the underlying block in interlocking relation to the bar.

3. An underfeed stoker having, in combination, a retort, a movable and a stationary grate section extended therefrom, each grate section comprising a grate bar and grate blocks mounted thereon, a tuyere block supported upon the retort and upon

the upper grate blocks of the grate sections having a slot and a cross bar in the bottom thereof, and a hook extended from the stationary grate bar through said slot and hooked over said cross bar.

4. An underfeed stoker having, in combination, a retort, a plurality of grate sections extending laterally therefrom, each grate section comprising a grate bar supported at its opposite ends, and grate blocks arranged thereon in steps so that the sides and one end of each overlying block are supported on the upper surface of the underlying block, lugs on each grate bar on which the other ends of the grate blocks are supported, depending hooks on the blocks, and lugs on the bar with which the hooks engage to prevent movement of the blocks away from the bar.

5. An underfeed stoker having, in combination, a retort and a plurality of grate sections extending laterally therefrom, each grate section comprising a grate bar, a plurality of grate blocks arranged in steps upon the grate bar and provided with hooks for securing them to the bar, and a plurality of tuyere blocks each supported at one side upon the upper grate blocks and at the other side upon the retort, interlocking members on the retort and tuyere blocks, and interlocking members on the grate sections and tuyere blocks.

6. An underfeed stoker having, in combination, a retort and a grate extending laterally from the upper edge of the retort comprising a plurality of grate bars, a series of grate blocks mounted upon each grate bar, interlocking members for binding the blocks on the bars, tuyere blocks along the edge of the retort, each of which overlies a plurality of grate blocks, interlocking members between the retort and tuyere blocks, and interlocking members between the tuyere blocks and grate blocks, whereby displacement of any portion of the grate involves the upward swinging of the grate structure about the edge of the retort.

7. An underfeed stoker having, in combination, a retort, a grate to which fuel is fed from the retort consisting of grate sections, each comprising an inclined grate bar, a series of horizontal grate blocks arranged thereon, interlocking members formed on the blocks and bar for locking the blocks to the bar, and a stop on each block for holding the underlying block in interlocking relation to the bar.

8. An underfeed stoker having, in combination, a retort, a grate to which fuel is fed from the retort consisting of grate sections, each comprising a grate bar, a series of grate blocks arranged thereon in steps, each block comprising a top plate slotted at its rear end to straddle the bar and project laterally therefrom, and a wall along the

- sides and front end adapted to rest on the underlying block and form an air passage between the top plates, and means for securing the blocks to the bar.
5. 9. An underfeed stoker having, in combination, a retort, a grate to which fuel is fed from the retort consisting of grate sections, each comprising a grate bar, a series of grate blocks arranged in steps and slotted to straddle the bar, interlocking members on the blocks and bar for locking the blocks to the bar, and a stop on each block for holding the underlying block in interlocking relation to the bar.
10. 10. An underfeed stoker having in combination, a retort, a grate to which fuel is fed from the retort consisting of grate sections, each comprising a grate bar, a series of grate blocks arranged thereon in steps, each block comprising a top plate slotted at its rear end to straddle the bar and a wall along its sides and front end adapted to rest on the underlying block, hooks on the blocks, lugs on the sides of the bar for supporting the rear ends of the blocks and for engaging the hooks, and a stop on each block for engaging the rear end of the underlying block.
15. 11. An underfeed stoker having, in combination, a retort, a grate to which fuel is fed from the retort consisting of grate sections, each comprising a grate bar having a spacing head at one end and a spacing foot at the other, a series of grate blocks arranged on the bars in steps, each block comprising a top plate slotted at its rear end to straddle the bar and a wall along its sides and front end adapted to rest on the underlying block, a plate on the foot on which the bottom block rests, means for securing the blocks on the bar, and a top block having an unslotted top plate and a closed inner end and an air chamber under the grate.
20. 12. An underfeed stoker having, in combination, a retort, a series of inclined grate bars at the side of the retort, spacing heads having closed ends at the upper ends of the bars, spacing feet at the lower ends of the bars, supports for the head and feet forming the walls of an air chamber below the bars, a series of grate blocks secured to each bar in steps and including a top block having a closed end registering with the end of the spacing head and tuyere blocks bridging the space between the retort and the top grate blocks.
25. 13. An underfeed stoker having, in combination, a retort, movable and stationary grate sections extending therefrom, each of which comprises a grate bar and a series of grate blocks secured thereon, and tuyere blocks, each of which is secured to the side of the retort and to the end of a stationary grate section and overlies the ends of the adjacent movable sections.
30. 14. An underfeed stoker having, in combination, a retort, movable and stationary grate sections extending therefrom, each of which comprises a grate bar and a series of grate blocks secured thereon, and tuyere blocks, each of which is secured to the side of the retort and to the end of a stationary grate section and overlies the ends of the adjacent movable sections.
35. 15. An underfeed stoker having, in combination, a retort, a support spaced from the side of the retort and forming a dividing wall, an air chamber on each side of the wall, a series of grate bars having spacing heads supported side by side on the support and forming a continuation of said dividing wall, a series of grate blocks on each bar the end block of which has a closed end forming a continuation of said wall, and tuyere blocks bridging the space between the side of the retort and said end grate blocks.
40. 16. An underfeed stoker having, in combination, a retort, two supports at the side of the retort forming the walls of an air chamber, grate bars having spacing heads and feet supported side by side on the supports, a series of grate blocks secured on each bar, the end block of which has a closed end forming with the closed ends of the heads a continuation of one wall of the chamber, and tuyere blocks bridging the space between the side of the retort and said closed end blocks.
45. 17. An underfeed stoker having, in combination, a retort, two supports at the side of the retort forming the walls of an air chamber, grate bars having spacing heads and feet supported side by side on the supports, a series of grate blocks secured on each bar, the end block of which has a closed end forming with the closed ends of the heads a continuation of one wall of the chamber, tuyere blocks bridging the space between the side of the retort and said closed ended blocks, and mechanism for reciprocating some of the grate bars.
50. 18. A stoker having, in combination, a retort, a plurality of grate bars, a plurality of grate blocks mounted thereon, and means for moving some of the grate bars including a rock shaft, cooperating racks and segments on the movable grate bars and shaft respectively, each segment having a yoke adapted to be slipped laterally over the shaft, and a block adapted to fit into the yoke to lock the yoke and segment in fixed relation to the shaft whereby any segment may be removed from the shaft without disturbing the remaining segments or grate bars.
55. 19. An underfeed stoker having, in combination, a retort, a plurality of grate bars, a plurality of grate blocks mounted thereon,

6
and means for moving some of the grate bars including a rock shaft and cooperating racks and segments on the movable grate bars and shaft respectively, each segment having provision whereby it may be removed from the shaft without disturbing the remaining segments.

- 10 20. An underfeed stoker having, in combination, a retort, a plurality of grate bars, and means for moving some of the grate bars including a rock shaft, cooperating racks and segments on the movable grate bars and shaft respectively, each rack and segment having an abnormal locating tooth and tooth space whereby the grate bars are positioned with relation to each other, and means for operating the rock shaft including a rocker shaft and gears on the rock shaft and rocker shaft respectively having an abnormal tooth and tooth space whereby the relation between the operating means and grate bars is determined.
- 15 25. An underfeed stoker having, in combination, a retort, a plurality of grate bars, and means for moving some of the grate bars including a rock shaft, a rocker shaft, and cooperating bevelled gears on each, the teeth on said gears comprising four segments, each being provided with an abnormal tooth and tooth space respectively.

22. An underfeed stoker having, in combination, a retort, a plurality of movable grates, a plunger for feeding the fuel lengthwise of the retort, a driven shaft, a crank on the shaft connected to operate the plunger, a second crank on the shaft, a rocker shaft, a rock shaft geared to the rocker shaft, cooperating segments on the rock shaft and grates, an arm on the rocker shaft and a link connecting said arm with said 40 second crank.

23. An underfeed stoker having, in combination, a retort, a grate extended laterally therefrom, an ash plate at the outer end of the grate, an ash supporting plate to which the ash plate is secured, having an open bearing, a square shaft upon which the ash supporting plate is mounted, and a bottom plate bolted to the ash supporting plate and securing the same to the square shaft. 45

24. An underfeed stoker having, in combination, a retort, a grate extended laterally therefrom, an ash plate, and means for supporting the ash plate including a square shaft, circular end bearings for the square shaft, open cylindrical collars for embracing intermediate points of the shaft and open bearings in which said open cylindrical collars are supported. 50 55

JOHN A. FLEMINGS.
